CLAIM

The ornamental design for a detachable inflatable headboard, as shown and described.

DESCRIPTION

FIG. 1 is a front and top perspective view of a detachable inflatable headboard, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front and top perspective view thereof, shown within an environment of use.

The broken lines in the figures illustrate portions of the detachable inflatable headboard that form no part of the claimed design. The broken lines of a bed in FIG. 8 shown in the drawings depict environmental structure that form no part of the claimed design.

1 Claim, 8 Drawing Sheets(56)
